UNITED STATES PATENT OFFICE.

HENRY GREY, OF DULUTH, MINNESOTA, ASSIGNOR TO THE AMERICAN UNIVERSAL MILL COMPANY, OF NEW YORK, N. Y.

APPARATUS FOR ROLLING BEAMS, GIRDERS, &c.

SPECIFICATION forming part of Letters Patent No. 632,181, dated August 29, 1899.

Application filed July 22, 1897. Serial No. 645,563. (No model.)

To all whom it may concern:

Be it known that I, HENRY GREY, of Duluth, St. Louis county, Minnesota, have invented certain new and useful Improvements 5 in Mills or Apparatus for Rolling Metallic Beams, Girders, Columns, &c.; and I do hereby declare the following to be a full, clear, and exact description of the invention, such as will enable others skilled in the art to which 10 it pertains to make and use the same.

My invention relates to improvements in mills or apparatus for rolling metallic beams, girders, columns, &c.

One object of my present invention is to prevent the formation of "crop ends" or projecting elongations of the web upon the finished product in rolling work of the character indicated.

A further object is to prevent cracking or 20 tearing of the flanges or heads of the work or other mutilation of the work during the rolling operation.

Another object is to more satisfactorily and 25 effectually guide the work and prevent dis- placement of the work during the passage of the latter through the mill and to obtain a perfectly straight product.

A further object is to reduce the cost of a 30 product of the character indicated and to successfully and accurately roll large and heavy blanks that cannot be successfully rolled by any mill or process heretofore devised.

With these objects in view and to the end 35 of realizing other advantages hereinafter ap- pearing, and particularly to the end in view of rolling large and heavy work accurately and economically, my invention consists in certain features of construction and combi- nations of parts hereinafter described, and 40 pointed out in the claims.

In the accompanying drawings, Figure I is 45 a top plan of my improved mill or apparatus, and portions are broken away in this figure to reduce the latter's size and to more clearly show the construction. Fig. II is a side ele- 50 vation of the same, largely in central vertical section. Fig. III is a top plan of roll system B, (employed in rolling the sides of the webs and heads or flanges of the work,) largely in horizontal section. Fig. IV is an elevation, partly broken away and in section, showing,

among other things, the operative connection between the top horizontal web-reducing roll and the vertical rolls employed to operate upon the outer sides of the flanges or heads 55 of the work. Fig. V is a top plan of the apparatus or machinery employed in simultaneously driving all of the horizontal rolls of the mill. Fig. VI is an elevation of the roll system employed in operating upon the edges 60 of the work's heads or flanges and showing also a portion of the machinery instrumental in driving the said rolls. Fig. VII is a view showing, detached, one of the screws em- 65 ployed in the adjustment of the top web-re- ducing roll, one of the screws employed in the adjustment of the upright flange-reduc- 70 ing rolls, and the screw employed in the ad- justment of the device employed in gaging or controlling the width of the work's flanges. 75 Fig. VIII is a side elevation, mostly in ver- tical section, of the mill's feed-table, that is provided with work-overturning apparatus. Fig. IX is a transverse vertical section of the 80 said table. Fig. X is a largely diagrammatic view showing the operative connection be- 75 tween the solenoid and a certain valve V, em- ployed in my improved mill, and illustrating also the connection in series of the said solenoid and the electric motor employed in the mill's 85 operation. Fig. XI is a side elevation, largely in vertical section, of cylinders and pistons employed in connection with a top guide for the work. Fig. XII is a vertical section of the casing containing the aforesaid valve V. 85 Fig. XIII is an elevation of two side guides arranged at opposite sides, respectively, of the work's path and engaged upon their outer side by simultaneously-operated pressure-ex- 90 erting devices shown in the said figure.

My improved apparatus or mill for rolling columns, beams, or girders comprises two systems of rolls—one roll system A for roll- 95 ing the edges of the heads or flanges of the column, beam, or girder (that is hereinafter termed the "blank" or the "work" or the "product") and another roll system B for rolling opposite sides of the flanges or heads and the web of the work. The two roll sys- 100 tems A and B are located in line and in such proximity to each other that the blank or work can be fed from the one system to the

other, and the work, in feeding it from the one to the other roll system, shall be received by the latter before it had left the former, and the rolling or operating surfaces of the 5 rolls of both systems of rolls are driven positively and in the direction required to feed in opposite directions alternately, and the work is given as many passes through the mill as are required to complete the rolling or shaping 10 of the work, and the blank or work is of course suitably heated preparatory to its introduction into the said rolling-mill, and the work is fed through the mill with its web arranged horizontally.

15 The roll system B comprises a top horizontal roll B', a bottom horizontal roll B², and two vertical side rolls D and D', arranged at opposite ends, respectively, of said horizontal rolls, and all of said rolls are positively rotated 20 in the direction required to feed the work, as will hereinafter appear. Roll B' is arranged horizontally and transversely of the work's path, in position to operate upon the upper side of the web of the work and upon 25 the inner sides of the work's flanges or heads above the web. Roll B² is arranged below and transversely of the work's path in position to operate upon the lower side of the work's web and upon the inner sides of the 30 work's heads or flanges below the web. The two upright rolls D and D' are arranged at opposite ends, respectively, of the work's path, in position to operate upon the outer side of the adjacent flange or head of the work. The 35 work C is shown in position in Figs. IV and IX. Rolls B' B² are of course rotated in opposite directions, respectively, and rolls D D' also rotate in opposite directions, respectively.

Roll system A comprises two rolls A' and A², arranged at the top and bottom, respectively, of the work's path, in position to operate upon the edges of the flanges or heads of the work—that is, the top roll A' operates upon the upwardly-presented edges, and the 45 bottom roll A² operates upon the downwardly-presented edges.

Two feed-tables C' and C² are arranged at opposite ends, respectively, of the work's path through the mill. Feed-table C' is located 50 adjacent to roll system B and is provided with any suitable number of suitably-driven feed-rollers C³. Feed-table C² is located adjacent to roll system A and comprises any suitable number of suitably-driven feed-rollers C⁴. 55 The work is fed from one of the feed-tables to the other feed-table and is passed in opposite directions alternately.

Any mechanism or apparatus suitable for 60 positively driving rolls B' B² of roll system B and rolls A' and A² of roll system A is provided, and in the case illustrated a trunnion A¹² of the lower roll A² of roll system A (see Fig. VI) is operatively connected, by means of a suitable coupling or connection A¹⁴, with 65 a suitably-supported horizontally-arranged shaft a, and a trunnion A³ of the upper roll

A' is operatively connected, by means of suitable coupling or connection A¹⁵, with a horizontal shaft a', arranged above and parallel with shaft a. Two spur-gears a² a³, operatively mounted upon shafts a and a', respectively, and having a corresponding number of teeth, mesh with each other, and gear a² meshes with a driving-pinion a⁴, operatively connected in any approved manner with a 70 suitably-supported and suitably-actuated driving-shaft a⁵. Hence rolls A' and A² are driven in opposite directions, respectively, as required. Another pinion a⁶ (see Fig. V) is operatively mounted upon driving-shaft a⁵ 75 and meshes with a spur-gear a⁷, operatively mounted upon a horizontal shaft a⁸, suitably supported at one side of and a suitable distance from shaft a⁵ and operatively connected, by means of suitable couplings or connections a⁹, with a spur-gear a¹⁰, arranged in line with shaft a⁸ and between said shaft a⁸ and the trunnion b' (see Fig. V) of the lower roll B² of roll system B, and any suitable couplings or connections b² establish operative connection 80 between said trunnion b' and gear a¹⁰. A spur-gear a¹¹ is arranged above and parallel and meshes with spur-gear a¹⁰. Gear a¹¹ is operatively connected by suitable couplings or connections b³ with one of the trunnions b⁴ of the upper roll B' of roll system B. The arrangement and relative size of the gear-wheels employed in establishing operative connection between the engine-shaft and rolls A', A², B', and B² are such that the rolling or operating surfaces of said rolls shall 90 be driven at the same speed, or nearly so.

The two rolls B' B² are driven in opposite directions, respectively, as already indicated, and the upper roll B' and the lower roll B² are 105 driven in the same direction as the upper roll A' and lower roll A², respectively, of roll system A, and hence the work can be fed from rolls A' A² to rolls B' B², or vice versa, according as the driving-shaft is actuated in the one 110 direction or the other, and the two systems of rolls are arranged in sufficiently close proximity to each other to enable the one system of rolls, as already indicated, to operate upon the work before the latter has left the other 115 roll system.

The bottom roll B² of roll system B is suitably supported from the two housings G G, arranged a suitable distance apart at opposite sides, respectively, of the work's path 120 and suitably tied together and braced apart by rods G³. It is obvious that for work of the character indicated the top roll B' must be adjustable vertically toward and from the bottom roll B², and the upright side rolls D 125 and D' must be adjustable apart, and it is also obvious that the said upright rolls D D' and the top roll B' must be adjusted simultaneously relative to the work's path, and I have discovered that the said upright side 130 rolls, in adjusting them apart simultaneously with the adjustment of the top roll, must be

moved more rapidly than the top roll in order to avoid long crop ends and torn or cracked flange edges on the finished product.

It is well known by those skilled in the art that the extensions of the web in the finished product beyond the ends of that portion of the product that is practically perfect and called "crop ends" in the trade are cut off and worth no more than scrap material, and 10 it will therefore be observed that any device or means instrumental in reducing the length of the crop ends from several feet to a few inches is of no inconsiderable importance. Crop ends should be avoided, if possible, and 15 this is practically accomplished in the mill that forms the subject-matter of this application, as will hereinafter more fully appear.

I have found that the best results are obtained by moving rolls D and D' about one 20 and one-fourth times as fast as the movement of the top roll B during the adjustment of said rolls. It is obvious that the rolls at the commencement of the operation of the mill are set as required to accommodate the 25 passage between them of the heated blank, and generally in the first pass of the work little more is accomplished than the straightening of the blank.

I would here remark that if the rolls D D' 30 in their movement toward and from each other were traveling at the same rate as the travel of the top roll toward and from the bottom roll all of said rolls will have traveled the same distance, and if, for instance, 35 the rolls were set, say, for a finished product to have one-half inch thickness of web and a half-inch thickness of flange the top horizontal roll B' would at the completion of the work be brought within that distance of the 40 bottom horizontal roll, and the side rolls D D' would be brought within that distance of the ends of the horizontal rolls that form, as already indicated, the inner sides of the flanges or heads and web of the work. Now if the top 45 roll in its movement toward the bottom roll moves at the same rate that each of the side rolls move in the latter's movements toward each other, and if the top roll's travel during the rolling of the work is two and one-half 50 inches, it follows that after the top roll has traveled two and one-half inches all of the rolls B' D D' will have traveled the same distance and the top roll B' will be three inches from the bottom roll B² and the side rolls D D' 55 will be the same distance—namely, three inches—from the flange-rolling surfaces of the horizontal rolls B' B². Now it is evident that if an even reduction of all parts of the work is to be effected and the travel of the top and 60 side rolls during the adjustments of the said rolls is the same, not only has no allowance been left for overcoming the distortion caused by the shear in cropping or cutting the blank, which is always much greater on 65 the flanges than on the web, but long crop ends will be had on the finished product. This subject of long crop ends will be readily

understood upon consideration of the fact that the flange-rolling surfaces of the horizontal rolls B' B² always revolve more slowly 70 than the peripheral or web-rolling surfaces of said rolls, because the flange-rolling surfaces of said rolls extend nearer to the axes of the rolls than the latter's web-rolling surfaces, and if the side rolls D D' are not caused 75 to work more vigorously than the horizontal rolls the finished product will probably be found cracked or torn at the edges of the heads or flanges and a great deal of material that should be equally distributed between 80 the web and flanges and thereby increase the length of the perfect product will have been robbed by the web-rolling surfaces of the horizontal rolls to form extensive elongations of the web at the ends of the product, which elongations or crop ends have to be cut off and are not worth any more than scrap material, and if the edges of the flanges or heads are mutilated the whole product is practically worthless and forms very expensive 85 scrap. Instead, therefore, of desiring only to reduce the flanges at the same rate as the web I have found it invaluable to reduce the flanges considerably faster than the web in order to make up for the much slower rate 90 of delivery at the points of the horizontal rolls from which the edges of the flanges are delivered from the speed of those parts of the horizontal rolls at which the web is delivered, and when the side rolls D D' are adjusted 95 toward each other more rapidly to the extent required than the movement of the top roll B' relative to the bottom roll B² it will be found that cracking or tearing of the edges of the flanges of the product will always be 100 avoided. Hence by traveling the side rolls about twenty-five per cent. more rapidly in the setting of the said rolls than the top roll in the aforesaid two-and-one-half-inch travel of the top roll during the reduction of the 105 work there will be room for the admittance of, say, at least three-eighths of an inch more material into each of the flanges and a further allowance of one-fourth inch to a side to accommodate any distortion of the blank or 110 work, and the latter can be finished without torn or cracked edges and without long crop ends on the finished part. The additional material going into the flanges, it will be observed, is instrumental in adding to the length 115 of the finished product (flanges as well as web) and is not robbed by the web for the objectionable purpose already indicated. Before referring to the mechanism employed for effecting the adjustment of said adjustable 120 rolls B', D, and D', I would remark that live surfaces should be presented to all sides of the work, and consequently all of said rolls and the bottom roll B² should be rotated positively and in unison. A suitable operative 125 connection between each of said upright rolls D and D' and the adjacent trunnion of the upper horizontal roll B' comprises, preferably, a horizontal friction-disk d, (see Figs.

III and IV,) operatively connected with the respective upright roll in any approved manner and preferably by the formation of interlocking lugs d^3 and D^3 upon said friction-disk 5 and the roll, respectively. The upright roll is bored centrally, as at D^4 , (see Fig. IV,) and the lugs D^3 are formed upon the upper portion of the surrounding wall of said bore. The friction-disk is therefore arranged within 10 or extends into the upper portion of the bore through the roll, and the aforesaid interlocking lugs are arranged vertically to accommodate an up-and-down movement or adjustment of the friction-disk for the purpose 15 hereinafter made more apparent. Said friction-disk d at its upper end is provided with an external annular beveled or conical friction-surface d^2 , that is frictionally engaged by a corresponding annular beveled or conical friction-disk B^3 , formed upon or operatively connected with the adjacent trunnion 20 of the upper horizontal roll B' .

The two friction-disks B^3 are reversely arranged and engage the inner or oppositely-located extremities, respectively, of the different friction-disks d , respectively, so that the two upright side rolls D D' shall be driven in opposite directions and in the direction necessary to render said upright rolls instrumental, as required, in feeding the work between them and between the horizontal rolls. By means of the vertical adjustability of disks d frictional engagement is maintained between said friction members and the friction-disks B^3 upon vertically readjusting the upper horizontal roll B' , that, it will be observed, is supported from the said disks. The means acting to elevate each friction-disk d and maintain frictional engagement between 35 said friction-disk and the engaging friction-disk B^3 comprises, preferably, a piston E , (see Fig. IV,) that is secured to the said disk d in any approved manner. The piston extends downwardly into the chamber f , formed in the vertical cylindrical lug or cylinder F , formed upon the inner end of a horizontally-arranged slide H , and upon said cylinder the upright roll that is operatively connected with the aforesaid friction-disk d is mounted. 40

A port or passage-way f' for conducting water or fluid under pressure to chamber f is formed in any approved manner within the lower head of said cylinder and communicates with the aforesaid chamber. The fluid under pressure within said chamber acts to force the piston upwardly, and thereby causes the horizontal friction-disk d to be held in frictional contact with the engaging friction-disk B^3 and support the top roll B' . A stuffing- 45 box F^4 is provided around the piston at and supported by the upper end of cylinder F and prevents upward leakage of the fluid under pressure from chamber f . Each housing G , near its lower end and at the top of the 50 trunnions of the lower horizontal roll, (see Figs. III and IV,) is provided with laterally and outwardly projecting brackets G' , that are

provided with suitably-constructed slideways G^2 , designed for slides H and arranged parallel, therefore, with the direction in which the side rolls D and D' are adjustable—that is, two horizontally-movable slides H H are arranged at the outer sides of the different housings, respectively. One of said slides carries roll D , and the other slide carries roll D' . Both slides H H are adjustable toward and from each other, and the two rolls D D' are moved, therefore, toward or from each other according as slides H H are actuated toward or from each other. Each slide H is 80 provided, preferably, with two screws H^2 , arranged parallel with the slideways for said slide and a suitable distance apart and operatively connected with the slide in any approved manner. Screws H^2 engage, preferably, correspondingly-threaded nuts I , confined or held stationary within recesses g' , formed in the outer sides of the aforesaid slideway-forming housing-brackets, and by this construction it is obvious that each slide 85 H and the roll supported thereby are adjusted toward or from the pair of horizontal rolls B , B^2 according as the engaging-screws are turned in the one direction or the other. Each slide H is provided, also, with a thrust-bearing J 90 for the upright roll, which bearing is constructed in any approved manner.

The upright screws L L (see Figs. I, II, and IV) engage correspondingly-threaded holes formed in the tops of housings G G and are 100 arranged to form stops that limit the upward movement or elevation of the upper horizontal roll B' . Saddles l are shown interposed between the lower ends of said screws and the trunnions of said roll. By this construction 105 it is obvious that upon turning screws L in the direction required to elevate them the upper roll B' will be elevated by the action of the fluid under adequate pressure upon pistons E , and upon turning the said screws in 110 the opposite direction the said roll will be lowered against the said pressure.

My present invention involves not only the travel of the side rolls D D' more rapidly than the movement of the top roll B' in the simultaneous adjustment of said rolls, but embraces, also, any device, mechanism, or apparatus whereby the screws L , instrumental in adjusting the top roll vertically, and the screws H^2 , employed in adjusting apart the side rolls, are operatively connected together in such a manner that they are shifted endwise simultaneously, and at the same time the side-roll-adjusting screws are shifted more rapidly, so that rolls D D' shall be moved more rapidly than roll B' in setting said rolls, and to this end in the case illustrated the threads of screws H^2 have twenty-five per cent. more pitch than the threads of the screws L , as shown in Fig. VII.

The mechanism employed for rotating screws L and H^2 is preferably as follows: Upon the upper end or portion of each screw L (see Figs. I, II, and IV) is operatively mount-

ed a worm-wheel L', that meshes with a worm M', formed upon a suitably-supported horizontally-arranged shaft M. The upper ends of screws L are in the case illustrated angular in cross-section and extend through corresponding holes in the central portions of the engaging wheels L', so that the said screws are capable of endwise movement independently of the said wheels L' without interrupting operative connection between the said wheels and screws. Upon the outer end of each screw H² of a slide H (see Figs. I, III, and IV) is operatively mounted a bevel-gear h², that meshes with a bevel-gear h³, operatively mounted upon a suitably-supported horizontally-arranged shaft h⁴. The connection between gears h² and screws H² is such also that the screws can shift endwise independently of the engaging gears without interrupting operative connection between the screws and gears. Shaft M is intergeared, as at m, (see Fig. I,) with the reversibly rotatable shaft m' of an electric motor m². Each shaft h⁴ is operatively provided, also, with a worm-wheel h⁵, that meshes with a worm h⁶, formed upon a suitably-supported upright shaft h⁷, that is intergeared at its upper end, as at h⁸, with the shaft M. By the construction just described it will be observed that all of the said screws L and H² are operatively connected with one and the same motor-shaft m' and are consequently movable in unison. All the gears and worm-wheels of the mechanism that establishes operative connection between shaft M and the said screws correspond diametrically, and the worms of the said mechanism correspond in diameter, so that all of the screws are rotated at the same speed when they operate. Hence in the case illustrated the more rapid endwise movability of screws H² is due solely to the greater pitch of the threads of the said screws. Of course the members of the mechanism establishing operative connection between the reversible shaft m' and screws H² and L are so arranged that the side rolls D D' and top roll B' shall be simultaneously shifted inwardly or outwardly, according as the said shaft is rotated in the one or the other direction, and the said rolls are set, as required at the commencement of the operation of the mill, upon a predetermined size of blank to form the initial passage-way between the said side rolls and between the top and bottom rolls for the said blank, and the said adjustable rolls are adjusted as required to reduce the said space after each subsequent pass of the said blank. Rolls A' and A^X of roll system A (see Figs. I and II) are of course arranged in the same vertical plane, and roll A' has its trunnions resting in half-boxes A⁴, movable up and down within the two upright housings A⁵, that are arranged at opposite sides, respectively, of the work's path. Half-boxes A⁴ rest upon and are consequently supported from any suitable number of upright bars or rods A⁶, operatively connected

at their lower ends with vertically-tilting weighted levers A⁷, whose weights A⁸ somewhat more than counterbalance the weight of roll A' and act in the direction required to elevate said roll. Saddles or blocks A⁹ rest upon the trunnions of roll A' above half-boxes A⁴, and suitably-operated screws A¹⁰ engage correspondingly-threaded holes in the tops of the housings and engage the upper surfaces of saddles A⁹ and not only limit the upward movement of roll A', but are instrumental in lowering the said roll against the action of weights A⁸. Roll A' is adjustable vertically, therefore, as required, preparatory to operating upon the edges of the heads or flanges of a predetermined piece of work. Screws A¹⁰ when they are rotated or turned are operated uniformly, and the mechanism employed for uniformly operating said screws comprises, preferably, two beveled gears A^a A^a, operatively mounted on the different screws, respectively, above the housings and meshing with beveled gears A^b, that are operatively mounted upon a horizontally-arranged shaft A^c, suitably supported above the housings, and the arrangement of said last-mentioned gears relative to gears A^a is such that the screws when the said shaft is rotated are simultaneously turned in the same direction.

A gage for regulating the width of the heads or flanges of the work is provided, and comprises, preferably, a collar i, (see Figs. I and II,) mounted upon the bottom roll A^X of roll system A at the under side of the path of and arranged to afford bearing for the web of the work between the paths of the work's flanges or heads. The central portion of roll A^X is provided, preferably, with an annular groove or recess A^d, and collar i is mounted upon roll A^X within the said recess. Said collar, therefore, affords bearing, as already indicated, for the work during the operation of rolls A' and A^X. The side walls of recess A^d prevent endwise displacement of the collar upon the roll A^X, and the portions of the roll A^X at opposite sides, respectively, of said recess are instrumental in operating upon the edges of the heads or flanges of the work. One of the rolling portions of roll A^X is keyed, as at A^e, (see Fig. II,) or otherwise removably secured to the remaining portion of the roll to accommodate the mounting of collar i upon the central reduced portion of the roll, and of course said keyed part of the roll is not applied until after the collar has been placed in position. Collar i is adjustable vertically, as required, to enable it to be lifted or elevated a suitable distance after each pass of the work, and thereby render roll A' capable of operating, as required, upon the upwardly-presented edges of the work's flanges or heads. The vertical adjustability of collar i is obtained, preferably, by having the collar's hole i', through which the central portion of roll A^X extends, elongated vertically, as shown in Fig. II. Roll A^X is supported from housings

A⁵ in any approved manner, and collar *i* is supported, preferably, by a saddle *i*², arranged below the collar and having its upwardly-facing surface arranged circumferentially of and concentrically with the collar, and anti-friction-rollers *i*³ are interposed between said surfaces of the saddle and the lower external surface of the collar that turns upon said rollers during the operation of the mill. Saddle *i*² has two sides *i*⁴ *i*⁴, arranged at opposite ends, respectively, of the collar, and the anti-friction-rollers *i*³ extend between and are supported from said sides. The means employed for adjusting or moving collar *i* vertically comprises, preferably, an upright screw *i*⁵, that extends through and engages a correspondingly-threaded nut *i*⁶ that is located a suitable distance below saddle *i*² and rendered stationary in any approved manner. A suitably-supported worm-wheel *i*⁷ is operatively connected in such a manner—for instance, by feather and groove *i*⁸—with screw *i*⁵ that the latter can move endwise independently of the said wheel *i*⁷ without interrupting operative connection between said wheel *i*⁷ and said screw *i*⁵. Worm-wheel *i*⁷ meshes with a worm *i*⁹, that is formed upon a suitably-supported horizontally-arranged shaft *i*¹⁰, (see Figs. I and II,) and shaft *i*¹⁰ is intergeared, as at *i*¹¹, with a suitably-supported shaft *i*¹², that extends diagonally to shaft *M* and is intergeared, as at *i*¹³, with the said shaft *M*. It will be observed, therefore, that screw *i*⁵ is operatively connected with the motor-shaft *m*', so that the setting or adjusting of collar *i* preparatory to each pass of the work for the purpose, as already indicated, of gaging or controlling the width of the work's flanges is effected simultaneously with the adjustment of the adjustable rolls of roll system B. Worm-wheel *i*⁷, worm *i*⁹, and gears *i*¹¹ *i*¹³ correspond diametrically with the worm-wheels, worms, and gears that officiate in establishing operative connection between shaft *M* and screws *L* *H*², so that screw *i*⁵ is rotated at the same speed as screws *H*² and *L*. Therefore if collar *i* is to be shifted about one-half as far as the top roll *B*' of roll system B, as desired, it follows that the threads of screw *i*⁵ (see Fig. VII) have fifty per cent. less pitch than the threads of the screws *L* employed in adjusting the said roll. The said collar or cylinder *i* will therefore in shifting rolls *B*' and *D* *D*' rise one-half as much as the said roll *B*' lowers, and this is desired inasmuch as the position of the said member *i* determines the width of the work's flanges. As the rolls *B*' *B*² dig into the web of the blank or work the distance between the upper side of the work's web and upper roll *A*' is increased in proportion, and this being the case, although there is no collar or cylinder *i* on said roll *A*', still as the work that is being operated upon can be turned at will, as will hereinafter more fully appear, it follows that the distance between member *i* and roll *A*' for the initial pass of the work is determined

by the position of the roll *A*' relative to the position of the said member *i*, and this distance is increased or decreased for the work's initial pass by raising or lowering the said roll *A*', according as wider or narrower flanges or heads upon the finished product are desired. The lowering of the top roll *B*' of roll system B will result in raising member *i* one-half of the distance traveled by the said roll *B*', and member *i* will consequently gage or control the width of the work's flanges or heads after the mill has commenced to operate. The function performed by member *i* is therefore primarily the gaging of the width of the work's heads or flanges, and as the work is turned over at suitable intervals, as will presently appear, it follows that the edges of the flanges of the finished product will be even. Two rollers *j* and *j*', (see Fig. II,) arranged transversely of the lower side of the work's path at opposite sides, respectively, of roll *A*', are instrumental in guiding the work to and from said roll system A, and the roll *j*', that is located between the said roll system A and table *C*² is a feed-roller that is suitably driven in the direction required to feed the work to and from the said roll system from and to the said table. The said table comprises any suitable number of feed-rollers *C*⁴, as already indicated, and the feed-roller at the inner end of the table is operatively connected by means of sprocket-wheels and chain *C*⁵ with feed-roller *j*'. Operative connection between the feed-rollers of the table is established, preferably, by shafting and gears *C*⁶, suitably driven to feed the work in the direction required. (See Fig. I.) To remove scales from the work that can be readily removed by a tumbling process, the work when it is upon table *C*² is automatically overturned any suitable number of times, and this process of tumbling the work is valuable also, as already indicated, to insure adequate operation on all of the edges of the work's flanges in roll system A.

The means employed for overturning the work upon table *C*² comprises, preferably, (see Figs. VIII and IX,) an oscillating shaft *C*⁷, that is suitably supported below and arranged horizontally and longitudinally of the table and is provided at two points, located a suitable distance apart, with two arms *C*⁸ *C*⁸, extending transversely of the table and arranged to engage the work upon the table from below and throw the work laterally against the inclined uprights or backs *C*⁹, with which the table is provided. Each arm *C*⁸ of shaft *C*⁷ is arranged to operate between two adjacent feed-rollers of the table, so that said rollers shall not interfere with the location and operation of said arm. Arms *C*⁸ in their normal or inoperative position are below the path of the work that in solid lines, Fig. IX, is shown resting upon the feed-rollers of the table and in dotted lines in same figure is shown thrown laterally against the inclined surfaces of backs *C*⁹, which inclined

surfaces extend upwardly and outwardly from their lower extremities. Each arm C⁸ has its outer portion bent or extending upwardly, so that said outer portion when the work is thrown against backs C⁹ shall overlap the work and prevent the latter from rebounding back into the same position upon the table, and the inclined surfaces of members C⁹ are sufficiently far from a perpendicular that the work when the work-tumbling arms are returned below the table will fall with its opposite side upon the table. The said overturning operation is repeated, if desired, any suitable number of times and is very effectual in shaking scales from the work.

The means for oscillating the work-overturning shaft C⁷ comprises, preferably, (see Fig. IX,) a mutilated gear or toothed sector C¹⁰, that is operatively mounted upon the shaft, preferably at some point between the two arms C⁸ C⁹, and said sector meshes with a reciprocating rack C¹¹, that is arranged transversely of the feed-table between two adjacent feed-rollers of said table and attached in any approved manner to the rod C¹² of the piston C¹³ of a hydraulic engine or motor C¹⁴.

Two suitably-formed bottom guides or bearings Q Q' (see Figs. I and II) for the work are provided at opposite sides, respectively, of rolls B' B² of roll system B at the under side of the path of the work. Guide Q' is arranged between roller j and roll B² and extends into close proximity to the said roll B². Guide Q is arranged between roll B² and table C' and extends into close proximity to the said roll. Said guides prevent downward displacement of the work in the latter's passage to and from roll system B. A top guide T for the work in the passage of the work from the roll system B to the roll system A is provided (see Figs. I and II) for the purpose of preventing the work from being thrown upwardly out of its path in said passage. Said guide consists, preferably, of an approximately horizontally-arranged heavy plate suspended over and in close proximity to the path of the upper side of the work's web and between the paths of the work's flanges. Guide T is located between the two roll systems and in close proximity to roll B' of roll system B. Guide T is movable vertically to accommodate its adjustment correspondingly and simultaneously with the vertical adjustment of the top web-reducing roll B'. To effect the movement of guide T simultaneously with and in the same direction as the vertical movement of roll B' and to prevent any injury to any parts by any upward blow received by said guide from the work in the passage of the work below the guide, the following construction is provided: The guide at or near its central portion is suspended by means of a rod or bar T', that depends from one end of a vertically-tilting weighted lever T² and is attached at its lower end to the

guide in any approved manner. Lever T² is supported from a vertically-movable slide T³, that extends between and engages vertical 70 slideways (not shown) formed upon housings G G. The said lever is fulcrumed, therefore, to any suitable member that is rigid with or supported from the said slide, that near each end is suspended from a piston T⁴, arranged 75 to operate within and endwise of an upright stationary cylinder T⁵, having closed ends. Two upright cylinders T⁵ T⁵ are provided, therefore, over opposite ends, respectively, of slide T³, and the latter is suitably attached 80 to the piston-rods T⁶, depending from the pistons within said cylinders. Each cylinder T⁵ (see Fig. XI) is provided with two lateral ports T⁷ and T⁸ at the upper end and the lower end, respectively, of the cylinder. The 85 lower port T⁸ connects the lower extremity of the cylinder's chamber with a pipe or pressure line T⁹, employed in supplying water or other fluid under adequate pressure into said chamber below the piston in said chamber. 90 The fluid-pressure upon pistons T⁴ from below acts to lift guide T, and I would here remark that the poise T¹⁰, with which lever T² is preferably provided, counterbalances, preferably, the aggregate weight of the guide T 95 and the connection between the lever and the said guide. Adjacent to each cylinder T⁵ is provided another stationary upright cylinder T¹¹, that is preferably integral with the said cylinder T⁵ and is closed at its lower end and 100 open at its upper end. A piston T¹² is arranged to operate within and endwise of each cylinder T¹¹, and the latter at its lower end is provided with a lateral port T¹³, that is required in the establishment of open relation 105 between the lower extremity of the chamber of the said cylinder and the port T⁷ of the adjacent cylinder T⁵. The cylinders T⁵, above the pistons therein, the cylinders T¹¹, below the pistons therein, and the connections between ports T⁷ and T¹³ are supplied with water or other suitable fluid from any suitable number of supply-pipes T¹⁴. Each piston T¹² has its rod T¹⁵ extending downwardly below the cylinder and operatively connected with an 110 arm l', projecting laterally from and rigid with the saddle l upon the adjacent trunnion of the top web-reducing roll B'. The said piston T¹², and consequently the guide T, will therefore move downwardly correspondingly with any 115 downward travel of the top web-reducing roll B'. It is obvious that, as already indicated, the top web-reducing roll B' and with it the flange-reducing rolls D D' are set, preparatory to the first pass of a heated blank that requires 120 reducing, the distance apart required for the first pass, which distance forms the largest work-receiving passage between said rolls during the reducing operation upon the blank, and said passage is rendered smaller preparatory to each successive pass of the work. It follows, therefore, that the work's top guide T must be correspondingly set preparatory to 125 every pass of the work. The operative con- 130

nection of pistons T^{12} with the saddles l on the top roll B' lowers the said pistons T^{12} , as already indicated, upon lowering the said roll B' , and water is thereby displaced from below said pistons in cylinders T^{11} into the upper ends of cylinders T^5 through the connections between said cylinders, and the water forced into said cylinders D^5 depresses the pistons T^4 against the power exerted by the water from the pressure-line, and thereby lowers the guide the distance required. Guide T bears against or abuts the under side of slide T^3 , as at T^{16} , Fig. II, so that the guide cannot tilt. After the work has had its finishing pass the rolls are again adjusted to enlarge the work-receiving passage between them as required for another blank, and the elevation of the top roll B' during said resetting of the rolls by the pressure upon them by the horizontal friction-disks d as soon as the screws L are backed up lifts pistons T^{12} , permits the displacement of water from the upper ends of cylinders T^5 into cylinders T^{11} , and accommodates the elevation of pistons T^4 by the power from the pressure-line, and thereby results in the corresponding elevation of the work's top guide T . It will therefore be observed that said guide is adjusted simultaneously and uniformly with the adjustment of the top roll B' . It is desirable to lock the said roll and the said guide in the desired adjustment, so that they cannot be displaced vertically during the pass of the work, and I interpose, therefore, a valve V (see Figs. I and XII) in the line of the pipe connection between cylinders T^5 and T^{11} , which valve controls continuity in the passage-way between each cylinder T^5 and the adjacent cylinder T^{11} . When therefore said valve is closed, water cannot pass between the said cylinders, and the said top roll and the said guide are locked against vertical displacement, and when the said valve is open water can pass between the said cylinders and accommodate the vertical adjustment of the said guide and roll. It is obvious therefore that valve V should be open simultaneously or practically simultaneously with the commencement of the endwise shifting of screws L and should be closed simultaneously or practically simultaneously with the cessation of the endwise movement of the said screws. Before proceeding to describe the mechanism preferably employed for operating valve V , I would remark that said valve is arranged, preferably, in a valve-casing V' , having a port V^2 , connected by means of a T V^3 with the two pipes V^4 V^4 . One of said pipes V^4 connects with the port T^{13} of one of cylinders T^{11} , and the other pipe V^4 is connected with the port T^{13} of the other cylinder T^{11} . The seat V^5 for the valve is formed at the inner end of said port V^2 , and the latter at its inner end connects with a passage-way V^6 , extending through the valve-casing and having its opposite ends connected with different pipes V^7 V^7 , respectively. One of pipes V^7 connects with the port T^7 of one of the cylinders T^5 ,

and the other pipe V^7 connects with the port T^7 of the other cylinder T^5 . By this construction it is obvious that when the valve is shifted off its seat open relation is established between cylinders T^5 and T^{11} , and said communication is interrupted when the valve is seated.

The valve V for establishing and interrupting communication between the chambers of adjacent cylinders T^5 and T^{11} has a stem V^8 , extending outside of the valve-casing and operatively connected at its outer end (see also Fig. X) with a tilting lever V^9 at any suitable point between the opposite ends of the lever, that is fulcrumed at one end, as at V^{10} , to any suitable support and at its opposite end is operatively connected by means of a rod or suitable connection V^{11} with the end-wise-movable core or cores of a solenoid V^{12} . A suitably-applied spring V^{13} acts to retain the core or cores of the solenoid in their outer or normal position and also acts to retain the valve V in its closed position, wherein the chambers of adjacent cylinders T^5 and T^{11} are not in open relation with each other and water cannot flow between said chambers, as already indicated. However, when an electric current traverses the solenoid the core or cores of the solenoid are moved against the action of the said spring and move lever V^9 in the direction required to open the valve, whereupon communication between said chambers is established as required to accommodate the flow of water from cylinders T^5 to cylinders T^{11} , or vice versa, according as roll B' is elevated or lowered. An electric current is caused to traverse the solenoid therefore in any approved manner simultaneously or practically simultaneously with the commencement of the operation of screws L L , so that the said cylinders shall be placed in open relation with each other simultaneously or practically simultaneously with the commencement of the operation of said screws, and the said solenoid is rendered inactive in any approved manner simultaneously or practically simultaneously with the cessation of the operation of screws L L , so that communication between the said cylinders shall be interrupted simultaneously or practically simultaneously with the cessation of said screws' operation. A desirable manner of simultaneously or practically simultaneously effecting operation of the solenoid and electric motor, and thereby move valve V simultaneously with the commencement of the said screws' operation, involves the arrangement of the solenoid and motor in series in one and the same electric circuit, as shown in Fig. X, and the electric current is controlled and reversed at pleasure by any approved controller having a current-reverser incorporated therein. Devices for controlling an electric current and reversing the latter's direction and the placing of electroreceptive devices in series are so well understood by those skilled in the art that the largely diagrammatic illustration in Fig.

X will be readily understood, and further description or illustration thereof in this application is considered unnecessary. The connection of the electric motor and solenoid in series is important therefore, because a disabling of either one of said electroreceptive devices would at once interrupt the flow of electric current and simultaneously or practically simultaneously interrupt the operation 5 of the other electroreceptive device, and consequently there is no liability of the operation of the screws when valve V is closed, nor is there any liability of the closing of the valve while the screws are operating.

15 Two side guides r^r for the work (see Figs. I, II, and III) extend from roll system B to and beyond roll system A and are arranged at opposite sides, respectively, of the work. Said guides r^r extend into close proximity 20 to the rolls of roll system B and are cut away at the top, below roll A', as at r' , to accommodate the location and operation of the said roll A'. Guides r^r extend a suitable distance beyond the outer side of roll system 25 A into suitable proximity to table C². Guides r^r are parallel, supported in any approved manner, adjustable or movable laterally, and operatively connected by suitably-applied bars, rods, or devices r^2 at points between 30 roll system B and roll system A with slides H and H, respectively, and hence said guides are moved apart or toward each other according as rolls D and D' are shifted toward or from each other and simultaneously with 35 and to the same extent as the movement of the said rolls D D'. The said guides r^r between roll system A and table C² are engaged upon their outer sides by extensions or members r^3 of pistons r^4 (see Fig. I,) 40 arranged and operated as required to move the said ends of guides r^r toward each other simultaneously with the shifting of rolls B' D D' and guide T. Guides r^r are set as required for the work's initial pass to accommodate 45 the passage of the heated blank between them, and after the first pass the said guides are shifted toward each other preparatory to each pass to reduce the width of the passage-way between them and continue to 50 properly perform their functions of guiding and preventing lateral displacement of the work during the operation of the mill upon the work. One member r^3 engages and is arranged at the outer side of and at right angles to one of the guides r , and the other member r^3 engages and is arranged at the outer side of and at right angles to the other guide r . Each piston r^4 is arranged to operate within a stationary horizontally-arranged 55 closed chambered cylinder r^5 , that at its outer end has its chamber connected with a pipe r^6 , employed for supplying water or other fluid under pressure to the piston in said cylinder, and thereby actuate the said piston in 60 the direction required to move the engaging guide r laterally and inwardly. Both pipes r^6 are connected with a main supply-pipe r^7 by a valve-casing r^8 , and a valve r^9 (see Fig. I) in said valve-casing interrupts and establishes communication between the main pipe r^7 and the branch pipes r^6 . The construction of said valve and valve-casing is substantially the same as the construction of valve V and valve-casing V, and the stem r^{10} of valve r^9 is operatively connected with 70 a vertically-tilting lever r^{11} , that is fulcrumed at one end, as at r^{12} , to any suitable support and has its opposite end connected with the core or cores of a solenoid r^{13} , that is electrically energized in any approved manner and 75 may be connected in series with the solenoid V¹² and the motor m^2 . Valve r^9 may, however, be operated in a different manner, if desired, and suffice it to state, therefore, that any suitably-operated valve for controlling 80 the supply of pressure to cylinders r^5 is employed and is opened to admit pressure or additional pressure to the said cylinders simultaneously or practically simultaneously with the inward shifting of rolls B' D D' and 85 guide T. The arrangement of parts is such that when an electric current traverses solenoid r^{13} valve r^9 is opened against the action of means, such, for instance, as a spring r^{14} , acting in the direction required to retain the 90 valve seated. Fluid can be removed from within cylinders r^5 through valved drain-pipes r^{15} , with which said cylinders are provided. (See Fig. I.)

Two side guides R R for the work (see Figs. I, II, III, and XIII) are provided between table C² and roll system B at opposite sides, respectively, of the work's path and extend into close proximity to rolls B' B². Each guide R is supported from the adjacent slide 100 H in any approved manner, and said guides are therefore moved toward or from each other according as the side rolls D and D' of roll system B are shifted toward or from each other. In the case illustrated each guide R 105 is supported at or near its inner end at R' (see Fig. III) in any approved manner from the supporting-slide H, but at its outer end is supported from the slide through the instrumentality of an endwise-movable bar or 110 rod R², (see Figs. III and XIII,) that is supported from and is movable with as well as independently of the slide. Said bar extends through a suitably-constructed stationary chambered cylinder R³, that is closed 115 at its ends and rigid with a lug G⁴, formed upon the adjacent housing G. The said bar extends easily through said lug and loosely through a lug H⁵, formed upon the slide. The outer end of the bar is round and screw-threaded, and two nuts R⁶ R⁷ are mounted 120 upon the bar at opposite sides, respectively, of the said lug H⁵ and farther apart than the opposite ends of the said lug. The bar within cylinder R³ is provided with a piston R⁴, arranged to move endwise of the cylinder's chamber and actuated inwardly, as required 125 to press the attached guide R laterally and inwardly by water or fluid under pressure 130

conducted into the outer end of the cylinder by a pipe R^5 , that communicates with the outer end of the cylinder's chamber. Nut R^6 constitutes a stop that limits the outward movement of the bar independently of the slide, and consequently the bar in its normal position has the said nut R^6 engaging the lug H^3 of the slide and is shifted inwardly with the slide in moving the side rolls toward each other. The space between lug H^3 and the outer nut R^7 of the bar is the distance that the bar can move independently of the slide, and hence the bar when under endwise pressure by the fluid introduced into cylinder R^3 will press the attached guide laterally and inwardly, and the two guides R^8 are pressed inwardly or toward each other during the last pass of the work to restrict the passage-way between the said guides at bars R^2 R^2 to approximately the width of the finished product, (measuring widthwise of the web,) so as to insure that the finished product will practically be perfectly straight. It follows, therefore, that bars R^2 R^2 are located at the mill's end at which the finished product is delivered, and the finishing pass is preferably from roll system A to roll system B, as in the case illustrated.

The two pipes R^5 , leading to the two cylinders R^3 , are connected with a main supply-pipe R^8 , that is provided with any suitably-constructed three-way valve R^9 capable of establishing and interrupting communication between cylinders R^3 and pressure-line R^8 and capable also of draining the said cylinders. The construction of valves of the character indicated is so well known that detailed description or illustration thereof is not considered necessary in this application.

40. What I claim is—

1. In rolling apparatus of the character indicated, the combination of the positively-rotated top and bottom rolls, and one of the said rolls being shiftable toward and from the other roll; the two positively-rotated upright side rolls arranged at opposite ends, respectively, of the top and bottom rolls and shiftable toward and from each other, and means whereby the said adjustable rolls are shiftable simultaneously and whereby the space between the side rolls is decreased or increased more rapidly than the space between the top and bottom rolls, substantially as and for the purpose set forth.

55. 2. In rolling apparatus of the character indicated, the combination with the positively-rotated top and bottom web-reducing rolls; the positively-rotated flange-reducing side rolls; mechanism for shifting one of the web-reducing rolls toward the other web-reducing roll; other mechanism for shifting the side rolls toward the web-reducing rolls, and means whereby the last-mentioned shifting mechanism is caused to shift more rapidly than the first-mentioned shifting mechanism, substantially as and for the purpose set forth.

60. 3. In rolling apparatus of the character in-

dicated, the combination of the positively-rotated top and bottom rolls B' B^2 , the two positively-rotated vertical or upright side rolls arranged at opposite ends, respectively, of the top and bottom rolls, means for vertically shifting the top roll, and means for more rapidly shifting the side rolls toward or from each other according as the top roll is lowered or elevated, substantially as and for the purpose set forth.

4. In rolling apparatus of the character indicated, the combination of positively-rotated top and bottom rolls, the positively-rotated side rolls, mechanism for shifting the top roll toward the bottom roll, other mechanism for shifting the side rolls toward the top and bottom rolls, and means whereby the last-mentioned shifting mechanism is caused to shift more rapidly than the first-mentioned shifting mechanism, substantially as and for the purpose set forth.

5. In rolling apparatus of the character indicated, the combination of the positively-rotated vertically-shiftable top roll B' ; the positively-rotated bottom roll B^2 ; the two positively-rotated vertical or upright side rolls arranged at opposite ends, respectively, of the top and bottom rolls and shiftable toward and from each other, and mechanism or apparatus whereby all of the said shiftable rolls can be moved inwardly or outwardly simultaneously and whereby the side rolls, when the said adjustable rolls are shifted, are caused to travel about twenty-five per cent. more rapidly than the top roll, substantially as and for the purpose set forth.

6. In rolling apparatus of the character indicated, the combination of the positively-rotated vertically-shiftable roll B' ; the positively-rotated bottom roll B^2 ; the positively-rotated side rolls arranged at opposite ends, respectively, of the top and bottom rolls and shiftable toward and from each other; means acting to elevate the top roll; screws for lowering said top roll; stationary members having correspondingly-threaded holes engaged by said screws; slides carrying the side rolls; screws connected with and arranged to shift said slides and having threads that have a greater pitch than the threads of the top-roll-adjusting screws; stationary nuts or members having correspondingly-threaded holes engaged by said slide-shifting screws, and mechanism for rotating all of the said screws at the same speed, or approximately so, and in the direction required to simultaneously move the said adjustable rolls inwardly or outwardly, substantially as and for the purpose set forth.

7. In rolling apparatus of the character indicated, the combination of a positively-rotated and vertically-shiftable horizontal top roll; a positively-rotated horizontal bottom roll; the two positively-rotated upright side rolls arranged at opposite ends, respectively, of the top and bottom rolls and shiftable toward and from each other; screws instrumental in shifting the top roll; screws instru-

mental in shifting the side rolls and having threads that have considerably more pitch than the threads of the top-roll-adjusting screws, and mechanism for simultaneously 5 rotating all of the said screws at the same speed or approximately so, substantially as and for the purpose set forth.

8. In rolling apparatus of the character indicated, the combination with a roll A' arranged to operate upon the upwardly-presented edges of the heads or flanges of the work; of an adjustable member arranged to afford bearing for the work's web as the work passes below the said roll and mechanism for 15 elevating the said member, substantially as and for the purpose set forth.

9. In rolling apparatus of the character indicated, the combination with the upper and lower rolls arranged to operate upon the 20 edges of the heads or flanges of the work, of a vertically-adjustable member arranged to afford bearing for the work's web between the said rolls, and mechanism for vertically shifting said member, substantially as and 25 for the purpose set forth.

10. In rolling apparatus of the character indicated, the combination with the two rolls arranged one above the other and arranged furthermore to operate upon the work's heads 30 or flanges, of a vertically-shiftable collar or cylinder upon one of said rolls between the rolling portions of the said roll, and mechanism for shifting the said cylinder or collar vertically, substantially as and for the purpose 35 set forth.

11. In rolling apparatus of the character indicated, the combination with the vertically-adjustable and positively-rotated upper horizontal roll A', and the positively-rotated 40 lower horizontal roll A^X; of a vertically-shiftable freely-turning collar mounted upon the central portion of the lower roll, and mechanism for shifting said collar, substantially as and for the purpose set forth.

45 12. In apparatus of the character indicated, the combination with the upper and lower rolls arranged to operate upon the edges of the heads or flanges of the work; of a vertically-adjustable rotatable collar mounted upon the 50 central portion of the lower roll, a saddle below the collar, antifriction-rollers interposed between the saddle and collar, a screw supporting the saddle, a stationary nut engaging the screw, and mechanism for turning the screw, substantially as and for the purpose set forth.

55 13. In rolling apparatus of the character indicated, the combination of a positively-rotated vertically-shiftable horizontal roll arranged to operate upon the web and flanges' inner sides, horizontal rolls arranged to operate upon the edges of the flanges and a vertically-adjustable member arranged to be engaged by the under side of the web in the 60 passage of the work between the last-mentioned rolls; of mechanism or apparatus whereby the said last-mentioned adjustable

member and the said adjustable roll can be moved simultaneously and in opposite directions, respectively, substantially as and for 70 the purpose set forth.

14. In rolling apparatus of the character indicated, the combination of the two web-reducing rolls arranged one above the other in position to operate upon opposite sides, respectively, of the web and upon the inner sides of the flanges, and one of said rolls being adjustable toward and from the companion roll, two positively-rotated upright side rolls arranged at opposite ends, respectively, of the 80 first-mentioned rolls and shiftable toward and from each other; two other rolls arranged one above the other in position to operate upon the edges of the work's flanges; a vertically-adjustable freely-turning collar or cylinder upon one of the flange-edge-rolling rolls between the rolling portions of the said roll, and means or mechanism whereby all of the 85 said adjustable members are simultaneously shiftable in the direction and to the extent 90 required, substantially as set forth.

15. In rolling apparatus of the character indicated, the combination with a roll system B having positively-rotated horizontal rolls B' B² arranged one above the other in position 95 to operate upon opposite sides, respectively, of the web and upon the inner sides of the flanges and having the top roll adjustable vertically, two positively-rotated vertical or upright side rolls arranged at opposite ends, respectively, of the first-mentioned rolls and 100 adjustable toward and from each other, another roll A' arranged to operate upon the upwardly-presented edges of the work, and a vertically-adjustable freely-turning collar 105 or cylinder arranged to afford bearing for the work's web below the last-mentioned roll; of mechanism for shifting the top web-reducing roll toward the bottom web-reducing roll, mechanism for shifting the side rolls toward 110 each other simultaneously with and more rapidly than the lowering of the adjustable web-reducing roll, and mechanism for elevating the aforesaid bearing-forming collar or cylinder simultaneously with and slower than 115 the lowering of the adjustable web-reducing roll, substantially as and for the purpose set forth.

16. In rolling apparatus of the character indicated, the combination with a roll system 120 B having two positively-rotated horizontal rolls B' B² arranged one above the other in position to operate upon opposite sides, respectively, of the web and upon the inner sides of the flanges, and having the top roll adjustable vertically, and two positively-rotated vertical or upright side rolls arranged at opposite ends, respectively, of the first-mentioned rolls and adjustable toward and from each other; of another roll system A having 125 two suitably-driven horizontal rolls A' and A^X arranged one above the other in position to operate upon the edges of the flanges, and a vertically-adjustable collar mounted upon 130

the central portion of the lower flange-edge-rolling roll, and mechanism whereby said collar and the top roll of the first-mentioned roll system are shifted simultaneously in opposite directions, respectively, and the said collar is shifted about one-half as rapidly as the said top roll, substantially as and for the purpose set forth.

17. In rolling apparatus of the character indicated, the combination with the upper vertically-adjustable web-reducing roll and the screws instrumental in shifting said roll, the rolls arranged to operate upon the edges of the flanges, the vertically-adjustable member instrumental in gaging or controlling the width of flanges during the operation of said last-mentioned rolls, and the screw instrumental in shifting the said gage and having threads that have less pitch than the thread of the aforesaid roll-adjusting screws, and mechanism whereby the said screws are rotated simultaneously at the same speed, or approximately so, and the arrangement of parts being such that the aforesaid gage and the aforesaid adjustable roll are shifted in opposite directions, respectively, during the operation of the said screws, substantially as and for the purpose set forth.

18. In a mill for rolling work of the character indicated, two rolls arranged to operate upon opposite sides, respectively, of the web and upon the inner sides of the flanges or heads and one of the said rolls being adjustable toward and from the companion roll, two rolls arranged to operate upon the outer sides of the different heads or flanges, respectively, and adjustable toward and from each other; a roll or rolls arranged to operate upon the edges of the flanges or heads; an adjustable member for gaging or controlling the width of heads or flanges during the operation of the flange-edge-rolling rolls, and mechanism whereby all of the said adjustable rolls and the said gage can be shifted simultaneously in the direction and to the extent required, substantially as shown, for the purpose specified.

19. In a rolling-mill of the character indicated, the combination with an upper roll A', a lower roll A^X, and a vertically-adjustable collar or cylinder i' mounted upon the central portion of the lower roll in position to engage the under side of the work's web; of a table C² adjacent to one side of said roll system and arranged at the under side of the work's path, and mechanism, devices, or apparatus for overturning the work upon the said table, substantially as and for the purpose set forth.

20. In a rolling-mill of the character indicated, the combination with the two suitably-driven horizontal and parallel rolls B' B² arranged one above the other in the same vertical plane, and the upper roll being adjustable vertically, and two suitably-driven vertical or upright side rolls D D' arranged at opposite ends, respectively, of the horizontal

rolls; of a vertically-adjustable guide T at the upper side of the work's path and in suitable proximity to the said upper roll, and means whereby the said guide and upper roll can be shifted up or down simultaneously, or practically so, substantially as set forth.

21. In a rolling-mill of the character indicated, the combination with a vertically-adjustable roll arranged to operate upon the work from above, and a guide arranged at the upper side of the work's path; of means whereby the said guide and the said roll are adjusted simultaneously or practically so, and electrically-operated devices for controlling the operation of said adjusting means, substantially as and for the purpose set forth.

22. In a rolling-mill of the character indicated, the combination with an adjustable roll arranged to operate upon the work, and an adjustable guide for the work; of means for shifting the said roll, an electrically-operated device for controlling the operation of said means, means for correspondingly shifting the guide, and an electrically-operated device for controlling the operation of said guide-shifting means, and both of said electrically-operated devices being arranged in the same electric circuit so that they shall simultaneously, or practically simultaneously, commence or cease to operate according as the circuit is established or interrupted, substantially as and for the purpose set forth.

23. In a rolling-mill of the character indicated, the combination with a vertically-adjustable roll arranged to operate upon the work from above, and a guide arranged at the upper side of the work's path; of a piston T⁴ arranged to operate within a closed upright chamber above the guide and instrumental in supporting the guide, a fluid-pressure line connected with the lower end of said chamber, another upright chamber arranged in suitable proximity to the aforesaid roll and closed at its lower end, a piston arranged to operate within said last-mentioned chamber and connected and movable with the said roll, a passage-way connecting the lower end of said last-mentioned chamber with, and above the piston in, the first-mentioned chamber, and the said passage-way and the connected portions of the chambers being supplied with water or other suitable fluid, and a valve for establishing and interrupting continuity in the said passage-way, substantially as and for the purpose set forth.

24. In a rolling-mill of the character indicated, the combination with a vertically-adjustable roll arranged to operate upon the work from above, and a guide arranged at the upper side of the work's path; of a piston T⁴ arranged to operate within a closed upright chamber above the guide and instrumental in supporting the guide, a fluid-pressure line connected with the lower end of said chamber, another upright chamber arranged in suitable proximity to the aforesaid roll and closed at its lower end, a piston arranged

to operate within said last-mentioned chamber and connected and movable with the said roll, a passage-way connecting the lower end of said last-mentioned chamber with, and 5 above the piston in, the first-mentioned chamber, and the said passage-way and the connected portions of the chambers being supplied with water or other suitable fluid, and an electrically-operated valve arranged in 10 the line of and controlling communication through the said passage-way, substantially as set forth.

25. In a rolling-mill of the character indicated, the combination with a vertically-adjustable roll arranged to operate upon the work from above, and a guide arranged at the upper side of the work's path; of two pairs of upright stationary chambered cylinders above the guide and the said pairs being arranged a suitable distance apart, one cylinder of each pair of cylinders being closed at the bottom and having a port in its lower portion and having a piston arranged to operate within and above the said port and 25 said piston being operatively connected with a member movable with the said roll, and the other cylinder of each pair of cylinders having two ports arranged a suitable distance apart, and being closed top and bottom, and having a piston that is arranged to operate between the said ports and operatively connected with the guide, and having its lower port connected with a pressure-line, a connection between the last-mentioned cylinder's upper port and the other cylinder's 35 port, said connection and the adjacent portions of the cylinders being supplied with water or other suitable fluid, and a valve arranged in the line of said connection, substantially as and for the purpose set forth.

26. In a rolling-mill of the character indicated, the combination with a vertically-adjustable roll arranged to operate upon the work from above, and a guide arranged at the 45 upper side of the work's path; of two pairs of upright stationary chambered cylinders above the guide and the said pairs being arranged a suitable distance apart; one cylinder T^{11} of each pair of cylinders being closed at the bottom and having a port in its lower portion and a piston arranged to operate within the cylinder and above the said port and connected and movable with the aforesaid roll; the other cylinder T^5 of each pair of cylinders being closed top and bottom and having two ports arranged a suitable distance apart and a piston arranged to operate between the said ports and operatively connected with the guide; a pressure-line connected 55 with the lower port of said last-mentioned cylinder; a pipe connection between the upper port of said last-mentioned cylinder and the port of the other cylinder; a single valve and valve-casing arranged and constructed to simultaneously establish or interrupt communication between the cylinders of both pairs of cylinders, and water or other suitable fluid

in the said pipe connections and connected portions of the cylinders, substantially as and for the purpose set forth.

27. In a rolling-mill of the character indicated, the combination with a vertically-adjustable roll arranged to operate upon the work from above, and a guide arranged at the upper side of the work's path: of two pairs of upright stationary chambered cylinders above the guide and the said pairs being arranged a suitable distance apart; one cylinder T^{11} of each pair of cylinders being closed at the bottom and having a port in its lower portion and a piston arranged to operate within the cylinder and above the said port and connected and movable with the aforesaid roll; the other cylinder T^5 of each pair of cylinders being closed top and bottom and having two ports arranged a suitable distance apart and a piston arranged to operate between the said ports and operatively connected with the guide; a pressure-line connected with the lower port of said last-mentioned cylinder; a pipe connection between the upper port of said last-mentioned cylinder and the port of the other cylinder; a valve arranged to interrupt or establish communication through the said pipe connection; water or other suitable fluid in the said pipe connection and connected portions of the cylinders; an electrically-operated device arranged to shift said valve in the one direction, and means acting to shift the valve in the opposite direction, substantially as and for the purpose set forth.

28. In a rolling-mill of the character indicated, the combination with a vertically-adjustable roll arranged to operate upon the work from above; screws instrumental in lowering the said roll; an electric motor operatively connected with the screws; means acting to elevate the roll, and a guide arranged at the upper side of the work's path: of two pairs of upright stationary chambered cylinders above the guide and the said pairs being arranged a suitable distance apart; one cylinder T^{11} of each pair of cylinders being closed at the bottom and having a port in the lower portion and a piston that is arranged to operate within the cylinder and above the said port and connected and movable with the aforesaid roll; the other cylinder T^5 of each pair of cylinders being closed top and bottom and having two ports arranged a suitable distance apart and a piston arranged to operate between the said ports and operatively connected with the guide; a pressure-line connected with the lower port of said last-mentioned cylinder; a pipe connection between the upper port of said last-mentioned cylinder and the port of the other cylinder; a valve arranged to interrupt and establish communication through the said pipe connection and connected portions of the cylinders; a solenoid arranged in series with the aforesaid motor; an operative connection between the valve and core or cores of the so-

lenoid and arranged and actuated to shift the valve in the one direction when an electric current traverses the solenoid, and means acting to shift the valve in the opposite direction, substantially as and for the purpose set forth.

29. In a rolling-mill of the character indicated, the combination of a suitably-operated vertically-movable slide arranged a suitable distance above the work's path, a lever fulcrumed to a member supported from said slide, a guide arranged at the upper side of the work's path and suspended from one arm of said lever, and a counterbalance attached to the lever's other arm, substantially as and for the purpose set forth.

30. In a rolling-mill of the character indicated, the combination of a suitably-operated vertically-movable slide arranged a suitable distance above the work's path, a guide arranged at the upper side of the work's path and suspended at one side of, and supported from, and abutting the underside of, the aforesaid slide, and means counterbalancing the said guide and the means instrumental in the suspension of the guide, substantially as set forth.

31. In a rolling-mill of the character indicated, the combination with a vertically-adjustable roll arranged to operate upon the work from above, and a guide arranged at the upper side of the work's path; of a vertically-movable slide or member arranged above the guide, means for shifting the said slide simultaneously with the shifting of the aforesaid roll, and a connection between the guide and the said slide, substantially as set forth.

32. In a rolling-mill of the character indicated, the combination with two guides arranged at opposite sides, respectively, of the work's path; of a valved pressure-line, cylinders, pistons, and connections between the pressure-line and pistons and between the pistons and guides, whereby the guides are moved toward each other upon establishing communication between the pressure-line and the cylinders, substantially as set forth.

33. In a rolling-mill of the character indicated, the combination with two guides arranged at opposite sides, respectively, of the work's path; of a pressure-line, cylinders, pistons and connections between the pistons and guides and between the pistons and pressure-line whereby the guides are moved toward each other upon establishing communication between the pressure-line and the cylinders, and an electrically-operated valve for controlling the supply of pressure to the cylinders, substantially as and for the purpose set forth.

34. In a rolling-mill of the character indicated, the combination with two guides arranged at opposite sides, respectively, of the work's path; cylinders arranged endwise to the outer sides of the guides, pistons arranged to operate within the said cylinders and having extensions or members engaging the outer

sides of the guides, means for supplying fluid under pressure to the said cylinders' outer ends, and mechanism for releasing the pressure in the cylinders, substantially as set forth.

35. In a rolling-mill of the character indicated, the combination with two side rolls D and D' arranged at opposite sides, respectively, of the work's path, in position to operate upon the outer sides of the work's flanges, and two slides arranged at opposite sides, respectively, of said path, and one of the said slides carrying one of said rolls and the other slide bearing the other roll: of laterally-movable and suitably-supported guides arranged at each side of the work's path and supported from the adjacent slide, and extending beyond the slides alongside the said path, devices at suitable points for exerting a pressure upon the outer sides of the said guides, and means for operating said pressure-exerting devices, substantially as and for the purpose set forth.

36. In a rolling-mill of the character indicated, the combination with a roll system arranged to operate upon the web and flanges' sides and comprising two rolls arranged to operate upon the work from opposite sides, respectively, of the work's path; two suitably-supported slides arranged at opposite sides, respectively, of said path, and movable toward and from each other, one of the slides carrying one of the aforesaid rolls and the other slide bearing the other roll, and another roll system located a suitable distance from the first-mentioned roll system and comprising a roll or rolls arranged to operate upon the flanges' edges: of two suitably-supported guides arranged between the two roll systems and at opposite sides, respectively, of the work's path and extending beyond the flange-edge-rolling roll or rolls, and suitably-operated means for simultaneously exerting a pressure upon the outer sides of said guides at a point beyond the last-mentioned roll or rolls, substantially as set forth.

37. In a rolling-mill of the character indicated, two laterally-adjustable guides arranged at opposite sides, respectively, of the work's path at the work-finishing end of the mill, of suitably-operated means for exerting a pressure upon the outer sides of said guides at a point beyond the rolls during the finishing pass of the work, substantially as and for the purpose set forth.

38. In a rolling-mill of the character indicated, two laterally-adjustable guides arranged at opposite sides, respectively, of the work's path at the work-finishing end of the mill; of a suitably-valved pressure-line, cylinders, pistons and connections between the pistons and guides and between the cylinders and pressure-line whereby a pressure upon the outer sides of said guides simultaneously can be exerted to restrict the passage-way between the said guides at the points at which pressure is applied, substantially as and for the purpose set forth.

39. In a rolling-mill of the character indicated, the combination with two laterally-movable guides R R arranged at opposite sides, respectively, of the work's path at the 5 work-finishing end of the mill; of a closed chambered cylinder arranged at the outer side of each guide, a piston within the said cylinder, a connection between the said piston and the adjacent guide, and means for supplying 10 fluid under pressure simultaneously to both cylinders, substantially as and for the purpose set forth.

40. In a rolling-mill of the character indicated, the combination with two rolls arranged 15 to operate upon the work from opposite sides, respectively, of the work's path, and two suitably-supported slides arranged at opposite sides, respectively, of the said path and adjustable apart, one of the slides carrying one of 20 the aforesaid rolls and the other slide bearing the other roll, and each of the slides having a lug H³; of two guides arranged at opposite sides, respectively, of the work's path, a suitably-operated pressure-exerting bar at the 25 outer side of each guide and arranged to press inwardly upon the said guide, said bar extending loosely through the lug of the adjacent slide and provided with two stop-forming members arranged at opposite ends, respectively, of the said lug and farther apart than 30 the said opposite ends of the lug, substantially as and for the purpose set forth.

41. In a rolling-mill of the character indicated, the combination with two rolls arranged 35 to operate upon the work from opposite sides, respectively, of the work's path, and two suitably-supported slides arranged at opposite sides, respectively, of the said path and mov-

able toward and from each other, one of the slides carrying one of said rolls and the other 40 slide bearing the other roll; of two suitably-supported guides arranged at opposite sides, respectively, of the work's path, and two pressure-exerting bars arranged to press the guides toward each other, said bars being movable with the different slides, respectively, and movable inwardly independently of the slides, substantially as and for the purpose set forth.

42. In a rolling-mill of the character indicated, the combination with two rolls arranged to operate upon the work from opposite sides, respectively, of the work's path, and two suitably-supported slides arranged at opposite sides, respectively, of the said path and adjustable apart, one of the slides carrying one of the aforesaid rolls and the other slide bearing the other roll, and each of the slides having a lug H³; of two guides arranged at opposite sides, respectively, of the work's path, a 60 suitably-operated pressure-exerting bar at the outer side of each guide and arranged to press inwardly upon the said guide, said bar extending loosely through the lug of the adjacent slide and provided with two stop-forming members arranged at opposite ends, respectively, of the said lug and farther apart than the said opposite ends of the lug, substantially as and for the purpose set forth.

In testimony whereof I sign this specification, in the presence of two witnesses, this 28th day of June, 1897.

HENRY GREY.
